UNITED STATES PATENT OFFICE.

CHRISTIAN GILSON, OF WILKINSBURG, PENNSYLVANIA, ASSIGNOR TO WESTINGHOUSE ELECTRIC & MANUFACTURING COMPANY, A CORPORATION OF PENNSYLVANIA.

TURBINE-BLADE.

1,283,496.

Specification of Letters Patent.

Patented Nov. 5, 1918.

Original application filed December 30, 1914, Serial No. 879,753. Divided and this application filed March 15, 1917. Serial No. 154,979.

To all whom it may concern:

Be it known that I, CHRISTIAN GILSON, a citizen of the United States, and a resident of Wilkinsburg, in the county of Allegheny and State of Pennsylvania, have made a new and useful Invention in Turbine-Blades, which is a division of application serially numbered 879,753, filed December 30, 1914, of which the following is a specification.

10 This invention relates to turbine blades and has for an object to produce a new and improved turbine blade which is integrally formed on a blade carrying element and is especially adapted to be employed in turbines, rotary compressors, pumps or similar apparatus.

15 A further object of the invention is to produce a new and improved turbine blade which may be easily manufactured and 20 which is strong, durable and rigid.

25 These and other objects, which will be made apparent throughout the further description of my invention, are attained by means of the blade described and illustrated herein.

30 In the drawings forming a part hereof, Figure 1 is a sectional view of a turbine rotor equipped with blades embodying my invention.

35 Fig. 2 is a fragmental sectional view of a rotor element along the line 2—2 of Fig. 3 and illustrates one step in the construction of blades made in accordance with my invention.

40 Fig. 3 is a fragmental side elevation of a blade carrying element and illustrates a step in the construction of blades made in accordance with my invention.

Fig. 4 is a fragmental transverse sectional view along the line 4—4 of Fig. 3.

45 Fig. 5 is a fragmental perspective view of the blade carrying element illustrated in Fig. 3.

Fig. 6 is a fragmental perspective view 50 illustrating blades formed in accordance with my invention.

Fig. 7 is a fragmental perspective view similar to Fig. 6 and illustrates the blades or buckets equipped with an outer shroud.

55 My new and improved blades or buckets may be employed for either rotating or stationary blades or buckets of turbines, compressors, or rotary pumps, and they are formed by milling or otherwise forming

relatively thin radially extending flat wings 55 on the peripheral face of the blade or bucket carrying member and then in shaping the wings so formed to the contour of a blade or bucket. It will be understood by those skilled in the art that while I have illustrated and described radially extending blades, this construction may also be employed for laterally extending blades, such for example as are employed in the usual form of radial flow turbines. 60 65

In Fig. 2, I have illustrated a portion of a rotor wheel 5, showing a rim 6 formed on the wheel from which the blades are to be cut. As shown in Figs. 3 and 4, the rim 6 of the rotor wheel 5, or blade carrying element, is 70 grooved adjacent to the body of the wheel and then milled to form flat transverse radially extending wings 7. The blank rim 6, as illustrated in Fig. 2, is so formed that a ridge 8 is left on the outer periphery thereof. 75 After the flat wings 7 have been milled the portion of the ridge remaining on each wing 7 forms a shroud engaging tip 9. As shown in Figs. 3, 4 and 5, the grooves formed in the blank rim 6 leave a shroud member 10 80 on each side of the rotor wheel 5 and spaced therefrom. The slots by which the flat wings 7 are formed are cut sufficiently deep that they meet the grooves and leave the shrouding members 10 supported by the 85 inner ends of the flat wings 7.

The forming of the blades from the flat wings 7 is accomplished by moving the shroud members 10 inwardly toward the blade carrying element and at the same time 90 slightly shifting both members 10 in the same direction circumferentially of the blade carrying element. This moves the radially extending edges of each wing 7 circumferentially of the blade carrying element, 95 and at the same time toward each other, and, by distorting the wings, produces blades having substantially uniformly curved fluid receiving and directing faces. It also produces a continuous shroud at the inner or 100 mounting ends of the blades, since the shroud members 10 are moved into contact with the blade carrying member. If desired the blades may then be shaped so that they will more accurately conform to the blade contour necessary for obtaining highest efficiency. Under ordinary circumstances blades so formed are sufficiently uniform 105

and approximate the required contour closely enough for all practical purposes after the shroud members 10 have been pressed inwardly and move circumferentially of the 5 blade carrying element.

For some purposes it is desirable to provide the blades with an outer shroud, therefore I have shown in Fig. 7 several blades equipped with an outer shroud member 11.

10 This shroud member 11 is provided with holes 12, through which the shroud engaging tips 9 project. The tips 9 are riveted over and securely lock the outer ends of the wings or blades 7 together so as to eliminate any 15 danger of vibration or deflection.

In Fig. 1, I have illustrated in section a completed rotor wheel having its outer periphery provided with blades constructed in accordance with my invention.

20 While I have described and illustrated the preferred embodiments of my invention, it will be apparent to those skilled in the art that various changes, modifications, additions and omissions may be made in the 25 apparatus illustrated without departing from the spirit and scope of my invention, as set forth by the appended claims.

What I claim is:

1. In combination with the rotor element 30 of a turbine, a plurality of blades integrally formed thereon and having integrally formed shrouding members on the inner ends thereof.

2. In combination with a blade carrying 35 element, a plurality of blades integrally secured thereto, and shroud members located adjacent to the element and integrally formed with the attached ends of the blades.

3. In combination with a blade carrying 40 element, a blade integrally formed with said element, and having an integrally formed shroud portion located adjacent to and flush with the fluid directing face of said element.

4. In combination with a blade carrying 45 element, a blade integrally formed with said

element and separately formed shroud members located on opposite sides of said element, and integrally formed with the blade.

5. In combination with a blade carrying element, a plurality of blades mounted 50 thereon and shrouding members integrally formed with the blades and independent of the element and held against the element by the blades.

6. In combination with a blade carrying 55 element, a plurality of blades of uniform cross section mounted thereon, said blades having integrally formed shrouding members on the inner ends thereof.

7. In combination with a blade carrying 60 element, a blade secured at a point between its tips to the blade carrying element, and shrouding members integrally formed with the blade and located on each side of the blade carrying element.

65 8. In combination, a blade carrying element, a plurality of blades integrally formed thereon, inner shrouding members integrally formed with the blades and independent of the blade carrying element, an outer shrouding member, and means for securing the outer shrouding member to a plurality of the blades.

9. In combination with a blade carrying 75 element, a blade integrally formed therewith, the point of attachment being at a point intermediate the tips of the blades, and independent shroud members located on opposite sides of the blade carrying member and coöperating with the outer face 80 thereof in forming a fluid directing passage between the blades, said shroud members being secured to the blades.

In testimony whereof, I have hereunto 85 subscribed my name this 13th day of March 1917.

CHRISTIAN GILSON.
